TRIMMING MACHINE

Charles G. Brostrom, Lynn, Mass., assignor to
United Shoe Machinery Corporation, Paterson,
N. J., a corporation of New Jersey

Application May 24, 1933, Serial No. 672,628

29 Claims. (Cl. 12—42)

This invention relates to machines for operating upon shoe parts and is illustrated as embodied in a machine for skiving the margins of covers secured to wood heels.

5 During the covering of wood heels it is customary to skive cover margins which have been inturned upon and cemented to the breast of the heel to a feather edge, in order that such cover margins may merge into the heel breast and therefore avoid the production of a noticeable shoulder in the heel breast after a separate cover which overlies the cover margins has been cemented to the breast of the heel. In like manner the cover margin which is inturned upon and 10 secured to the attaching face of the heel is usually skived to a feather edge in order to insure that the convex heel seat of the shoe shall engage the central part as well as the margins of the attaching face of the heel when the heel has been attached to the shoe. By skiving the cover margins the flesh surfaces of such margins are exposed, thereby providing surfaces against which the breast cover may be effectively cemented.

15 It is an object of the present invention to provide an inexpensive and compact machine which may be effectively used to skive a shoe part such, for example, as the margin of a cover cemented to a wood heel.

With the above object in view and in accordance with a feature of this invention the illustrated machine is provided with a flexible cutter, members to flex a portion of the cutter, means to guide a shoe part relatively to the flexed portion of the cutter, and mechanism to oscillate the 20 flexed portion of the cutter thereby to skive the shoe part guided past the cutter.

25 In the illustrated construction a cutter made of a narrow band of steel is bent into a loop, one end of which is held stationary while the other end is oscillated, the work being fed to a suitably curved portion of this loop so that a draw cut of curved outline is produced.

It is desirable that the cutting edge of the cutter should always be sharp enough to produce 30 a clean cut. According therefore to another feature of the invention, means are provided for replacing a length or section of the oscillating cutter which has become somewhat dull by a new length or section which is sharp. To this end 35 the illustrated cutter has the form of a strip knife and means are provided by which the end portions of the knife may be maintained in the form of coils mounted upon drums from one of which the knife may be fed to the other.

40 It is desirable that the curved path of the cut

of the cutter be maintained substantially uniform so as to produce a uniform scarf on the work. To this end there is provided, in accordance with another feature of the invention, means for bracing the operative section of the cutter to cause its curve to remain substantially constant during the oscillation of the cutter. In the illustrated construction the operative section passes between edge guides, over a curved bed which engages the lower side of the cutter and beneath an adjacent member which engages the upper side of the cutter. The operative section of the oscillating cutter is thus compelled at all times to maintain a fixed curvature.

45 This and other features of the invention including certain details of construction and combinations of parts will be described as embodied in an illustrated machine and pointed out in the appended claims.

50 In the drawings,

Fig. 1 shows a side elevational view of the illustrated machine, portions of which have been broken away;

Fig. 2 is a front elevational view of the machine;

Fig. 3 is a plan view of the machine;

Fig. 4 shows a sectional view taken along line IV—IV of Fig. 1 and illustrates a pair of rolls for feeding the strip knife of the machine; and

Fig. 5 is a perspective view showing the operating head of the machine in the process of skiving a heel cover margin which has been applied to the attaching face of a heel.

55 The illustrated machine is described with reference to the skiving of margins 20, 22 (Fig. 5) of covers which have been cemented to wood heels 24. In covering wood heels, it is customary to apply a single piece of covering material to the side and rear faces of the heel 24 and then adhesively to secure the projecting margins 20, 22 of the cover upon the attaching face 26 and the breast 28, respectively of the heel. For reasons already stated, it is common practice to skive the margins 20, 22 of the cover after the cover has been cemented to the heel 24.

The illustrated machine which may be advantageously used to perform the above-mentioned operation, is provided with a flexible cutter or knife 30 having a U-shaped or loop portion 32, a clamp 34 to secure one of the ends of the loop portion 32 against movement, a hollow rod 36 provided with a split jaw portion 38 secured to the other end of the loop portion 32 and mounted for reciprocation, members 40, 42 (Fig. 5) to brace a curved operating section 44 of the knife 30, and

spaced gages 46, 48 constructed and arranged respectively to engage the rim of the attaching face 26 and the breast 28 of the heel, thereby to guide the same past said curved operating or 5 braced section 44 for skiving the margin of the cover.

The operating parts of the illustrated machine are supported upon a frame 50 which may be bolted to a table 52 of suitable height. It is desirable 10 that the cutting edge 54 (Fig. 5) of the knife 30 be kept sharp, otherwise there is a tendency for the cover to be torn where it is folded over the rim of the attaching face 26, due to the movement of the heel past the braced 15 section 44 of the knife. In order, therefore, that an operating section 44 having a dull cutting edge may readily be replaced by a section having a sharp cutting edge, the illustrated flexible knife is elongated and may be referred to as a strip 20 knife. The sharpened lengths of the strip knife 30 are supplied from a drum or magazine 56 upon which the knife 30 is mounted in the form of a coil 58. Sections of the knife 30 which have become dull and have been replaced by sharpened 25 sections may be moved lengthwise of the split rod 36 and wound around another drum or magazine 60 which is positioned at the rear end of the machine. Each of the drums 56, 60 is mounted for rotative movement upon a rod 62 which is secured by a nut 64 to bosses 66 of the main frame 30. Each of the drums 56, 60 is frictionally held in engagement with its respective boss 66 against free rotation by a spring 68 one end of which carries a friction block 70 and the other end of 35 which abuts against the enlarged head of the rod 62.

To insure that the U-shaped or looped portion 32 may be of predetermined length, the machine is provided with a gage or arm 72 (Fig. 1) which 40 is pivoted on a pin 74 carried by the main frame and which, during the operation of the machine, is normally thrown back to the position shown in Fig. 1. Hinged to the upper end of the arm 72 is an apron 76 which assumes a vertical position 45 when the arm 72 has been moved into its lowered position such as shown in dotted lines in Fig. 1. The lower end 78 of the arm 72 is eccentrically mounted upon the pin 74 and when the arm 72 is in its raised position the end 78 engages the 50 clamp 34 which is hinged at 80 to the main frame and forces the knife 30 against the main frame thereby to hold the upper end of the U-shaped or looped portion 32 of the knife against movement. When the arm 72 is swung to a forward 55 or lowered position, the lower end 78 thereof is moved away from the clamp 34 and permits a pair of feed rolls 82, 84 which are operated by a thumb screw 85 and are constructed of rubber or like material, to draw a section of the knife 60 30 from the drum 56 of the machine.

The jaw portions 38 may be forced together to clamp the lower end of the U-shaped portion 32 of the knife for reciprocating the same lengthwise or may be permitted to release the knife 30 65 preparatory to sliding the same lengthwise. The split jaw portion 38 of the hollow rod 36 flares (Fig. 5) toward the front face of the rod and is shaped for reception in a tapered recess 86 formed in the forward end of a plunger 88 which 70 is mounted for reciprocation in the frame of the machine and is secured by a clamp screw 90 (Fig. 1) to a bifurcated block 92 pivotally connected to an eccentrically mounted operating arm 94. Power may be supplied to the operating arm 94 75 through an eccentric 96 carried by a transversely

extending shaft 98 which is driven by a belt 100 connected to an electric motor 102.

In order to slide the hollow rod 36 and its split jaw portion 38 relatively to the plunger 88 to release the knife 30 or to clamp the same, the rod 36 is provided with a pair of axially spaced collars 104, 106 (Fig. 1) adapted to receive a cam 108 which is eccentrically mounted upon a pin 110 carried by the block 92 and is provided with a handle 112 for moving the collars 104, 106 and therefore the rod 36 with respect to the block 92.

The gage 46 comprises angularly disposed members provided with faces 114, 116 (Fig. 5) which are arranged to engage the rim of the attaching face 26 of the covered heel. The gage 15 48, which may also be referred to as a rest, serves as a guard to prevent damaging the heel and may also be utilized to assist the gage 46 in positioning the margin 20 of the cover relatively to the braced section 44 of the cutter 30. It will be noted that the member 40 which braces the outside face of the knife 30 has its knife-engaging face 118 inclined to the face 114 of the gage, the forward end of the inclined face 118 being slightly spaced from the face 116. In order to 25 brace the knife 30 against the pressure of the heel 24 the member 46 is raised at both sides of the surface 118 to form a notch 119 for receiving the cutter 30, the blunt edge of which engages the member as the heel is moved past the cutter. 30

A work support 120 for carrying the combined gage and cutter-bracing member may be adjusted in directions of arrows 122 (Fig. 1) relatively to the U-shaped portion 32 of the cutter 30 after releasing a set screw 124, which is in 35 threaded relation with the main frame and the end of which engages a spline 126, by turning a thumb screw 128 which is journaled in the main frame and turns a gear 130 constructed and arranged to mesh with a rack 132 of an arm 134. 40 The work support 120 may be raised or lowered relatively to the U-shaped cutting portion 32 by turning a thumb nut 136 in threaded relation with a post 138 of a platform 140, which post passes through a cylindrical recess of a bifurcated 45 portion 142 of the arm 134. The support 120 is provided with arcuate flanges 144 constructed and arranged to cooperate with correspondingly shaped recesses of the platform 140 and may be adjusted along the recesses by turning a worm 50 146 which is in meshing relation with a rack 148 on the bottom face of the support 120. The gage 46 may be adjusted relatively to the support 120 by turning a thumb screw 150 in threaded relation with a screw 152 carried by the gage 46, 55 which screw slides through a cylindrical bore of the support 120. It will be clear from the foregoing that the gage 46 may be moved to various positions relatively to the U-shaped portion in accordance with the work being trimmed in the 60 machine.

In order to skive the margins of the cover of the heel to a feather edge the operator after properly adjusting the gages 46, 48 and insuring that the braced section 44 of the U-shaped portion is 65 sharp, presents the heel to the knife as shown in Fig. 5 and turns the heel progressively to move the margin 20 past the braced section 44 of the knife thereby to skive the margin to a feather edge. 70

Having thus described my invention, what I claim as new and desire to secure by Letters Patent of the United States is:

1. A trimming machine having, in combination, a flexible cutter, members constructed and ar- 75

ranged to maintain flexed at all times a portion of the cutter, means to guide one of two superimposed shoe parts relatively to the flexed portion of the cutter, and mechanism to oscillate said flexed portion of the cutter thereby to skive one of said shoe parts guided by said means past said portion.

2. A trimming machine having, in combination, a flexible cutter, means for bending the cutter to provide a flexed portion thereof, a clamp to secure a portion of the cutter against movement, means to position a shoe part relatively to the flexed portion of the cutter, and mechanism to oscillate the flexed portion of the cutter.

15. 3. A trimming machine having, in combination, a flexible cutting blade having a loop portion, members to brace a section of the loop portion against substantial distortion under pressure of a shoe part, means to position the shoe part relatively to said section of the blade, means to hold the blade stationary at one end of the loop portion, and mechanism to reciprocate portions of the blade at the other end of the loop portion thereby to trim the shoe part as it is moved past the blade.

4. A trimming machine having, in combination, a flexible cutting blade, means to flex the blade to provide a loop portion, spaced members arranged at opposite sides respectively of the loop portion of the blade to brace a section of the blade, a clamp constructed and arranged to hold a portion of the blade stationary, and mechanism to reciprocate another part of the cutting blade.

5. A trimming machine having, in combination, 35 a flexible cutting blade, means to flex the blade to form a loop portion, members spaced lengthwise and arranged at opposite sides of the blade to brace a section of the loop portion, a clamp to secure one end of the loop portion against movement, means to position one of two superimposed shoe parts relatively to the braced section of the blade, and mechanism to reciprocate the braced section of the loop portion.

6. A trimming machine having, in combination, 45 a flexible strip knife, means by which the end portions thereof are maintained in the form of coils from one of which the knife may be fed to the other, mechanism constructed and arranged to reciprocate an intermediate portion of the knife relatively to the coils, and means arranged to control the presentation of a work piece to said intermediate portion of the knife.

7. A trimming machine having, in combination, 55 a flexible strip knife, means by which the end portions thereof are maintained in the form of coils from one of which the knife may be fed to the other, means to flex an intermediate portion of the knife, mechanism arranged to impart longitudinal reciprocation to said intermediate portion of the knife, and means arranged to control presentation of a shoe part to said intermediate portion of the knife thereby to trim said shoe part by a skiving cut.

8. A trimming machine having, in combination, 65 a flexible strip knife, a magazine to receive an elongated end portion of the knife, members to form a U-shaped operating portion in the knife, feed rolls to draw a section of the knife from said magazine to replace the U-shaped operating portion of the knife when such portion has become dull by a sharpened portion of the knife, a clamp located between said rolls and the U-shaped portion to secure the knife against movement after a new section of knife has replaced 70 the old and to release the same preparatory to

operating the feed rolls, and means to reciprocate the U-shaped portion to trim a work piece presented to the U-shaped portion of the knife.

9. A trimming machine having, in combination, 5 a flexible strip knife, a drum to receive a sharpened length of knife, means to flex a portion of the knife to provide a U-shaped operating portion thereof, a pair of resilient feed rolls constructed and arranged to unroll a section of the knife from the drum for replacing a U-shaped operating portion of the knife which has become dull by a sharpened portion of the knife, means constructed and arranged to release the knife preparatory to operating the feed rolls and to clamp a portion of the knife positioned between the drum and the U-shaped portion, means to position a work piece relatively to the U-shaped portion, and means to oscillate the U-shaped portion of the knife thereby to trim the work piece as the same is moved past the knife.

10. A trimming machine having, in combination, 10 a flexible strip knife, means to flex the knife to provide a U-shaped operating portion thereof, means to oscillate said U-shaped portion, means constructed and arranged to control the 15 presentation of a work piece to the U-shaped portion, and a gage to measure the length of the U-shaped operating portion.

11. A trimming machine having, in combination, 20 a flexible strip knife, means to flex the knife thereby to form a U-shaped operating portion therein, a gage to measure the size of the U-shaped operating portion, a cam to clamp one end of the U-shaped portion, and mechanism to reciprocate the opposite end of said U-shaped portion, 25 said gage and said cam being mounted for movement as a unit to cause the clamp to release the knife when the gage is in operating position and to cause the knife to be clamped when the gage has been moved to an inoperative position.

12. A trimming machine having, in combination, 30 a flexible strip knife, a magazine to receive a sharpened knife portion, another magazine to receive a knife portion which has become dull, means to reciprocate an intermediate portion of the knife, means arranged to control presentation of work to the intermediate portion, and means to feed the knife from the first-named magazine to the second-named magazine.

13. A trimming machine having, in combination, 35 a flexible strip knife, magazines to carry the end portions respectively of the knife and from one of which the knife may be fed to the other, members to flex an intermediate portion of the knife, clamping mechanism to secure one 45 part of the intermediate portion of the knife against movement, a member to reciprocate another part of the intermediate portion of the knife, and a gage to control the presentation of the work to said intermediate portion.

14. A trimming machine having, in combination, 50 a flexible strip knife, magazines to carry the end portions respectively of the knife and from one of which the knife may be fed to the other, means to flex an intermediate portion of the knife to provide a trimming portion thereof, clamping mechanism to secure one part of the intermediate portion of the knife against movement, and a member to reciprocate another part of the intermediate portion of the knife to skive 55 a portion of a cover which has been secured to a heel as the heel is moved past said trimming portion, said member being constructed and arranged to clamp the knife and also to release the 60 knife preparatory to moving the same lengthwise.

- to replace a dull section of the knife by a sharp section.
15. A trimming machine having, in combination, a flexible strip knife, means by which the end portions of the knife are maintained in the form of coils from one of which the knife may be fed to the other, means to flex an intermediate portion of the knife, a member to clamp one part of the intermediate portion of the knife against movement, mechanism to reciprocate another part of the intermediate portion of the knife, and means to control the presentation of a work piece to said intermediate portion of the knife, said mechanism comprising a cam-operated clamp to secure the knife for movement with the mechanism or to release the knife with respect to such mechanism.
16. A trimming machine having, in combination, a flexible strip knife, means by which the end portions of the knife are maintained in the form of coils from one of which the knife may be fed to the other, means to flex an intermediate portion of the knife, a member to clamp one part of the intermediate portion of the knife against movement, mechanism to reciprocate another part of the intermediate portion of the knife, and means to control the presentation of a work piece to said intermediate portion of the knife, said mechanism comprising a sleeve having a flared portion, a split plunger comprising a wedge portion mounted within the sleeve and adjustable relatively to the same, and a cam to adjust the plunger relatively to the sleeve to cause the wedge-shaped portion of the plunger to engage the flared portion of the sleeve and thereby to clamp the knife.
17. A trimming machine having, in combination, a flexible knife, means to flex the knife thereby to form a curved portion thereof, means to reciprocate the curved portion of the knife lengthwise of its cutting edge, and a gage comprising a pair of faces which are disposed in angular relation to each other, said gage being constructed and arranged for engagement with an edge of a covered heel to guide the heel past said curved portion thereby to skive portions of a cover laid upon the heel.
18. A trimming machine having, in combination, a flexible knife, means to flex the knife to form a loop portion thereof, means to secure one part of the loop portion against movement, mechanism to reciprocate another part of the loop portion lengthwise, means to brace a section of said portion, and a gage comprising a pair of faces disposed in angular relation with respect to each other and constructed and arranged for engagement with an edge of a heel to which a cover has been applied to guide the heel past said section thereby to skive portions of the cover which are located adjacent to said edge.
19. A trimming machine having, in combination, a flexible knife, means for flexing the knife to form a U-shaped portion thereof, a clamp to secure one of the ends of the U-shaped portion against movement, a member to reciprocate the other end of said U-shaped portion, members to brace a section of the U-shaped portion of the knife, a gage provided with angularly disposed faces for engaging an edge of a heel, and a rest arranged for engagement with one of the faces of the heel to cooperate with said gage for guiding the heel past said section thereby to skive the cover laid upon said heel.
20. A trimming machine having, in combination, a flexible knife, means to bend the knife to provide a flexed portion thereof, mechanism to move a section of the flexed portion lengthwise of its cutting edge, and a gage having angularly disposed supporting members for engaging an edge of a heel, one of said members being provided with a notch to receive the flexed portion of the knife.
21. A trimming machine having, in combination, a flexible knife, means for flexing the knife to form a curved portion thereof, mechanism to reciprocate said knife, a gage provided with a V-shaped portion arranged to engage an edge of a heel upon which a cover has been laid, the vertex of said V-shaped portion being spaced from the flexed portion of the knife, and the gage being constructed and arranged to guide the heel past said knife to trim the laid cover positioned adjacent to said edge by a skiving cut.
22. A trimming machine having, in combination, a flexible knife, means for flexing the knife, spaced members arranged to engage opposite sides of the knife to brace a flexed portion of the same, means for reciprocating said braced portion of the knife, and a gage having angularly disposed faces for engaging the rim of the attaching face of a heel upon which a cover has been laid, the braced portion of the knife being slightly spaced from the line of intersection of said faces and being constructed to skive a portion of the cover laid upon said attaching face by a skiving cut which starts adjacent to the rim of the heel as the heel is moved past the knife.
23. A trimming machine having, in combination, a flexible knife, means for flexing the knife, spaced members arranged to engage opposite sides of the knife to brace a flexed section thereof, means for reciprocating the braced portion of the knife, a gage having angularly disposed faces for engaging the rim of the attaching face of a heel upon which a covering has been laid, and a rest constructed and arranged to engage the breast face of the heel and to cooperate with the gage in guiding the heel past the braced portion of the knife thereby to skive the cover laid upon the attaching face by a cut which starts adjacent to the rim of the attaching face of the heel and terminates in a feather edge.
24. A trimming machine having, in combination, a flexible knife, means for flexing the knife to form a U-shaped portion thereof, a clamp to secure one of the ends of the U-shaped portion against movement, a member to reciprocate the other end of the U-shaped portion, members to brace a section of the U-shaped portion of the knife, a gage constructed and arranged for engagement with an edge of a heel, a rest arranged to engage one of the faces of the heel and to cooperate with said gage thereby to guide the heel past said section for skiving the cover laid upon said heel, and means for adjusting said rest relatively to the gage in accordance with the shape of the heel the covering of which is to be skived.
25. A trimming machine having, in combination, a flexible knife, means for flexing the knife to form a U-shaped portion thereof, a clamp to secure one of the ends of the U-shaped portion against movement, a member to reciprocate the other end of the U-shaped portion, members to brace a section of the U-shaped portion of the knife, a gage provided with angularly disposed faces for engaging an edge of a heel upon which a cover has been laid, a rest constructed and arranged for engagement with one of the faces of the heel and to cooperate with said gage for guid-

ing the heel past said section thereby to skive the cover laid upon said heel, and means for adjusting said gage and said rest relatively to the braced section of the knife and relatively to each other.

26. A trimming machine having, in combination, a flexible knife, spaced members arranged to engage opposite sides of the knife for flexing the same thereby to provide a curved knife section, means for reciprocating said knife section, and a gage having angularly disposed faces constructed and arranged to engage the rim of the attaching face of a heel to which a cover has been secured, the curved section of the knife being slightly spaced from the line of intersection of said faces and being constructed to skive a portion of the cover upon the attaching face by a skiving cut which starts adjacent to the rim of the heel as the heel is moved past the knife, said gage being angularly adjustable with respect to the knife.

27. A machine for operating upon parts of boots and shoes having, in combination, an elongated flexible cutter, means for bending a section of the cutter into a curve, means for oscillating the curved section lengthwise of the cutter, and means for adjusting the cutter lengthwise of itself to replace a section which has become dull by one which is sharp.

28. A trimming machine comprising two coil-supporting devices spaced apart and cooperatively related to support, respectively, two coiled portions of a flexible strip-knife having an intermediate coil-connecting portion, and knife-operating mechanism including movable clamping means arranged to clamp and operate said intermediate portion of the knife.

29. A trimming machine comprising two coil-holders spaced apart and arranged to support, respectively, two coiled portions of a flexible strip-knife having an intermediate coil-connecting portion, and knife-operating mechanism including clamping means movable relatively to said coil-holders and arranged to clamp said intermediate portion of the knife.

CHARLES G. BROSTROM.
